(Cl. D9—2)

To all whom it may concern:

Be it known that we, Madeleine Lodewick and Mildred Lodewick, citizens of the United States, residing at 156 East 52nd Street, in the county of New York, city of New York, and State of New York, have invented a new, original, and ornamental Design for a Combination Toothbrush and Casing Therefor, of which the following is a specification, reference being had to the accompanying drawing, forming part thereof.

Fig. 1 is a perspective view of a combination toothbrush and casing therefor, showing our new design.

Fig. 2 is a perspective view thereof, with the brush head ready to be inserted in the casing for use.

We claim:

The ornamental design for a combination toothbrush and casing therefor, as shown and described.

MILDRED LODEWICK,
MADELEINE LODEWICK.
